(No Model.)

P. MEDART.

Belt Pulley.

No. 241,555.

Patented May 17, 1881.

FIG. 2.

FIG. 1.

ATTEST:

Robert Burns
Philip Medart

INVENTOR:

Philip Medart

UNITED STATES PATENT OFFICE.

PHILIP MEDART, OF ST. LOUIS, MISSOURI, ASSIGNOR OF ONE-HALF TO
WILLIAM MEDART, OF SAME PLACE.

BELT-PULLEY.

SPECIFICATION forming part of Letters Patent No. 241,555, dated May 17, 1881.

Application filed January 31, 1881. (No model.)

To all whom it may concern:

Be it known that I, PHILIP MEDART, a citizen of the United States, residing at St. Louis, in the State of Missouri, have invented certain new and useful Improvements in Belt-Pulleys; and I do hereby declare that the following is a full, clear, and exact description of the same, such as will enable others skilled in the art to which it appertains to make and use the same, reference being had to the accompanying drawings, and to the letters of reference marked thereon, forming a part of this specification.

This invention has for its object the formation of a belt-pulley of a light, strong, and durable construction; and this invention consists, first, in the formation of the rim of the pulley wholly of paper, either in the form of paper-board, papier-maché, vulcanized fiber, or other form of paper-board met with in the art; secondly, in the provision, in connection with the rim of a belt-pulley, of a stiffening-ring of metal, paper, &c., placed at the edges of the rim, so as to impart additional stiffness to the same; thirdly, in the formation of a belt-pulley with arms of wrought metal cast into the hub, with their outer ends bent so as to form bracket-lugs for the attachment of the rim, as will hereinafter more fully appear; fourthly, in certain details of construction, as will hereinafter more fully appear.

In the drawings, Figure 1 is a side elevation. Fig. 2 is a transverse axial section.

In the drawings, A represents the hub, in which are cast the inner ends of the flat metal arms B of the pulley. These arms are arranged alternated or staggered, as shown, so as to allow of their being cast in the hub during the process of casting the same. These arms are bent at their outer ends, so as to form bracket-lugs b, for the attachment of the rim C by the rivets c, the lugs b being arranged crosswise to the rim, as shown, so as to form a wide support for the same.

D are stiffening-rings arranged at the edges of the rim C, for imparting stiffness to the same. This feature is very useful and valuable in cases where a pulley is required to be constructed with a very wide rim.

The rim C is made wholly of paper, in any of the forms met with in the trade, such as paper-board, plain or chemically treated, vulcanized fiber, &c. This material I have found

forms a very evenly balanced rim, and at the same time is cheap, durable, and effective. 55

In constructing my improved pulley the arms are cast in the hub in a straight form. The spider thus formed is placed in a former, which bends the lug b concentric with the axis of the pulley, after which the rim is bent into 60 the required circular shape and attached to said lugs by rivets c, so as to complete the pulley.

I am aware that prior to my invention wag-on-wheels have been constructed with alternated arms, such construction being shown in Patent No. 19,951, granted April 13, 1858, to B. A. Rogers. I am also aware that prior to my invention completed pulleys have had their rims faced or covered with strips of paper to 70 prevent the slipping of belts, &c. I therefore do not claim such constructions or combinations, broadly; but,

Having thus fully described my invention, what I claim as new, and desire to secure by 75 Letters Patent, is—

1. A rim for belt-pulleys formed wholly of paper, substantially as herein described, and for the purpose set forth.

2. A rim for belt-pulleys provided with stiffening-rings D at its edges, substantially as described, and for the purpose set forth. 80

3. A belt-pulley composed of a rim formed wholly of paper, and a rimless spider having bracket-lugs at the ends of its arms for the 85 attachment of the rim, substantially as described and set forth.

4. A belt-pulley composed of a rim, C, and a rimless spider consisting of a cast-metal hub, A, and arms B, having their outer ends 90 bent so as to form bracket-lugs b, for the attachment of the rim, as described, and for the purpose set forth.

5. A belt-pulley composed of a rim, C, formed wholly of paper, and a rimless spider 95 consisting of a cast-metal hub, A, and arms B, arranged in an alternated direction, and having their outer ends bent so as to form bracket-lugs b, for the attachment of the rim, as described, and for the purpose set forth. 100

Signed at St. Louis, in the State of Missouri, this 26th day of January, 1881.

PHILIP MEDART.

In presence of—

W.M. MEDART,
ROBT. BURNS.
